UNITED STATES PATENT OFFICE.

CHARLES L. GEORGE, OF FINDLAY, OHIO, ASSIGNOR TO THE BUCKEYE TRACTION DITCHER COMPANY, OF FINDLAY, OHIO, A CORPORATION OF OHIO.

SIGHT-ARM ATTACHMENT FOR EXCAVATING-MACHINES.

1,395,810.

Specification of Letters Patent.

Patented Nov. 1, 1921.

Application filed October 14, 1920. Serial No. 416,853.

To all whom it may concern:

Be it known that I, CHARLES L. GEORGE, a citizen of the United States, and a resident of Findlay, in the county of Hancock

5 and State of Ohio, have made an invention appertaining to Sight-Arm Attachments for Excavating-Machines; and I do hereby declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

This invention relates to trench digging or excavating machines and particularly to a sight-arm attachment for use in connection therewith.

20 It will be understood that in the use of sight-arms in connection with machines of this character it is the practice to maintain a predetermined depth of trench by keeping a sight-arm on the machine on a level 25 with a set of ground stakes or level finders positioned in the line of the trench.

The object of my invention is the provision of a sight-arm attachment for use in connection with the pivoted chain carrying 30 frames or booms of excavating machines of the bucket and chain type, which attachment is simple and efficient in its construction and easily and quickly adjustable relative to the carrying frame to suit the depth 35 at which it is desired to dig a trench.

The invention is fully described in the following specification, and while, in its broader aspect it is capable of embodiment in numerous forms, a preferred embodiment 40 thereof is illustrated in the accompanying drawings, in which—

Figure 1 is a side elevation of an excavating machine embodying the invention, with parts removed. Fig. 2 is an enlarged sectional detail of a portion of the sight-arm adjusting means, with parts broken away. Fig. 3 is a fragmentary side elevation thereof. Fig. 4 is an outer end elevation of the sight-arm carrying frame with its sight-arm 45 suspended therefrom. Fig. 5 is an enlarged fragmentary side elevation of the sight-arm carrying frame and its adjustable support. Fig. 6 is an enlarged top plan view of the forward end portion of the sight-arm carrying frame and sight arm attached, and Fig. 50

7 is a plan view of the sight arm carrying frame with the sight arm and adjusting means in connection therewith and with parts broken away.

Referring to the drawings, 1 designates 60 an excavating machine frame supported by front and rear sets of wheels 2 and 3, the latter, in the present instance, being of the apron tractor type. A super-frame 4 is carried by the main frame over the rear end 65 portion thereof and has a boom or pivoted frame 5, which guides and carries the excavating bucket chain, projecting rearwardly and downwardly therefrom for vertical swinging adjustment about a pivot 70 center 6. The raising and lowering of the frame 5 is controlled by a cable or cables 7

in the usual or in any suitable manner. The sight arm carrying frame 8, comprising 75 a pair of transversely spaced longitudinally extending bars 9 and connecting cross pieces 10, is pivoted at its inner end adjacent to the frame pivots 6, and in the present instance to brackets 11 projecting from the frame 5, and projects rearwardly from such 80 brackets over the frame 5 for vertical swinging movement.

The sight-arm frame is supported in adjusted relation to the frame 5 by a pair of bars 12, which pivotally rise from respective 85 sides of the frame 5 and slidably project at their upper ends through pivoted guide blocks 13 carried by the frame 8. The blocks 13, in the present instance, have journal portions 14 Fig. 2 mounted in the respective ends of a tubular cross-member 15, which connects the bars 9, 9 of the frame 8 intermediate the ends thereof and in the present instance adjacent to their forward ends, and is rigidly attached to said bars by 90 U-bolts 16 Figs. 3 and 5. A locking pin 17 is mounted in each end portion of the cross member 15 and projects at its outer end through the respective block 13 in intersecting relation to the opening thereof through 95 which the adjusting bar 12 projects. The bars 12 have a plurality of longitudinally spaced openings 18 therethrough through any one of which the locking pin 17 may project to retain the bar 12 in adjusted relation to the block 13. Each locking pin 17 is yieldingly held in bar locking position by the action of a coiled expansion spring 19 thereon. The inner end of each locking pin 17 has a flexible cable or draft member 20 100

105

105

110

projecting inwardly therefrom to near the center of the cross-member 15 and thence around a respective sheave 21 and laterally from the member 15 through a side opening 5 therein, the cables thence extending to any suitable point for operation of the same. The sheaves 21 are carried by the cross-member 15 partially within the opening thereof. It is evident that to change the 10 adjustment of the sight-arm carrying frame 8 with respect to the bucket chain carrying frame 5, it is only necessary to pull on the cables 20 to simultaneously withdraw the locking pins 17, 17 from the supporting bars 12, 12, and to then move the frame 8 to the 15 desired position when the locking pins are released to engage a registering set of openings in the bars 12.

The frame 8 at its outer end carries an 20 L-shaped member 22, one end of which connects and is pivotally mounted in the forward ends of the frame bars 9, 9, while the other arm of the member 22 hangs down and carries a laterally projecting sight arm 23. 25 The arm 23 is adjustable longitudinally of the pendant arm of the member 22 and is secured in adjusted position by a set screw 24, or in any other suitable manner.

It is evident in the use of my invention 30 that the greater the depth of the trench being dug the greater will be the angle between the frames 5 and 8, which angle is obtained by a relative adjustment of the frame 8 and supporting bars 12. It is also 35 evident that the level of the trench being dug is maintained by sighting across the arm 23 and alining it with the sight portions of the ground stakes.

I wish it understood that my invention is 40 not limited to any specific construction, arrangement or form of the parts, as it is capable of numerous modifications and changes without departing from the spirit of the claims.

45 Having thus described my invention, what I claim as new, and desire to secure by Letters Patent, is,—

1. In an excavating machine, a truck frame, a bucket chain carrying boom pivotally projecting from the truck frame, for 50 vertical swinging adjustment, a sight-arm

carrying frame pivotally projecting over the boom longitudinally thereof for vertical swinging adjustment to vary the angle between the two, a sight arm carried by the 55 sight arm carrying frame, and adjustable means connecting the sight arm carrying frame and boom for adjustably maintaining them in predetermined fixed relation.

2. In an excavating machine, a bucket 60 chain carrying boom pivotally mounted for vertical swinging movements, a sight-arm carrying frame pivotally projecting from the inner end portion of the boom rearwardly thereover for vertical swinging ad- 65 justment and carrying a sight-arm at its outer end, and adjustable means connecting the boom and frame for maintaining a pre-determined relative adjustment thereof.

3. In an excavating machine, a truck 70 frame, a bucket chain carrying boom and a sight-arm carrying frame projecting in the same direction from the truck frame for vertical swinging movements relative to the truck frame and to each other, supporting 75 bars pivotally rising from the boom at the sides of the frame in sliding connection therewith, and manually operable means carried by the frame for releasably engaging the bars to retain them in adjusted relation 80 to the frame.

4. In an excavating machine, a bucket 85 chain carrying boom mounted for vertical swinging adjustment, a sight-arm carrying frame pivotally projecting rearwardly of the boom from a pivot adjacent to its inner end and for vertical swinging adjustment relative thereto, a cross member carried by the frame, blocks pivotally carried by the ends of the cross member for vertical rock- 90 ing movements relative thereto and having openings therethrough, supporting bars pivotally rising from the boom and slidingly projecting through the block openings, and locking members carried by the cross mem- 95 ber and operable to releasably engage the bars within the blocks to retain them in adjusted relation.

In testimony whereof I have hereunto signed my name to this specification.

CHARLES L. GEORGE.
